Scott D. Locke, Esq.

(57) **CLAIM**

The ornamental design for a watch, as shown and described.

DESCRIPTION

FIG. 1 is a front view of the watch.

FIG. 2 is a top view of the watch.

FIG. 3 is a left side view of the watch.

FIG. 4 is a right side view of the watch.

FIG. 5 is a back view of the watch; and,

FIG. 6 is a bottom view of the watch.

The broken lines in FIG. 6 are used to show portions of the watch that do not form part of the claimed design.

1 Claim, 2 Drawing Sheets

FIG. 1

FIG. 3

FIG. 2

FIG. 4

FIG. 5

FIG. 6
